MOWER DRUM

Samuel G. Cassady, Tucker, Ga., assignor to John A. Chambliss, Chattanooga, Tenn.

Filed Dec. 11, 1967, Ser. No. 9,719

Term of patent 14 years

Int. Cl. D15—03

U.S. Cl. D40—1

Fig. 1

Fig. 2

Fig. 3

FIG. 1 is a perspective view of the mower drum as seen from one side, with the center portion being removed for convenience of illustration;

FIG. 2 is a perspective view of the mower drum as shown in FIG. 1 after 180° rotation about its longitudinal axis;

FIG. 3 is an end elevational view of the mower drum.

I claim:

The ornamental design for a mower drum, as shown and described.
